Int. Cl. D15—06

U.S. Cl. D49—11

FIG. 1 comprises perspective views of the top, front, and one side panel of the steam-vacuum power unit of the system and the top, front, and one side face of the floor supported cleaning head of the system with the vacuum and solution hoses between the units in fragmentary form to denote the indefinite length of such hoses;

FIG. 2 comprises perspective views of the top, back and opposite side faces of the power unit and the back, top, and opposite side faces of the floor supported cleaning head with the vacuum and solution hoses between the units shown in fragmentary form to signify the indefinite length of the hoses;

FIG. 3 is a perspective view of the top, front, and one side face of the hand supported cleaning head of the system with fragmentary showings of the vacuum and solution hoses extending to the power unit when the hand unit is coupled with the power unit; and

FIG. 4 is a perspective view of the back, top, and opposite side faces of the hand supported cleaning head with fragmentary showings of the solution and vacuum hoses extending to the power unit when the hand-held unit is coupled with the power unit.

I claim:

The ornamental design for a carpet and upholstery steam-vacuum cleaning system, substantially as shown and described.
